UNITED STATES PATENT OFFICE

MARIE R. OBERTING, OF MINERAL POINT, MISSOURI

DESIGN FOR A LAMBREQUIN

Application filed February 19, 1931. Serial No. 38,721. Term of patent 7 years.

To all whom it may concern:

Be it known that I, MARIE R. OBERTING, a citizen of the United States, residing at Mineral Point, in the county of Washington and State of Missouri, have invented a new, original, and ornamental Design for a Lambrequin, of which the following is a specification, reference being had to the accompanying drawing, forming part thereof.

The figure is a perspective view of the lambrequin showing my new design.

I claim:—

The ornamental design for a lambrequin, as shown.

MARIE R. OBERTING.
